[57] CLAIM

The ornamental design for a catamaran type boat and boat hull, as shown and described.

DESCRIPTION

FIG. 1 is a bottom perspective view of the back of the new ornamental design of my catamaran type boat and boat hull;

FIG. 2 is a bottom perspective view of the front of the design of FIG. 1;

FIG. 3 is a top plan view thereof;

FIG. 4 is a side elevational view thereof, the other side being a mirror image;

FIG. 5 is a bottom plan view thereof;

FIG. 6 is a front elevational view thereof;

FIG. 7 is a back elevational view thereof;

FIG. 8 is a perspective view from above of a catamaran type boat with the boat hull design of FIG. 1;

FIG. 9 is a top plan view of my design of FIG. 8;

FIG. 10 is a side plan view of my design of FIG. 8, the other side being a mirror image;

FIG. 11 is a bottom plan view of my design of FIG. 8;

FIG. 12 is a front elevational view of my design of FIG. 8; and,

FIG. 13 is a back elevational view of my design of FIG. 8.
